FIG. 1.

FIG. 2

FIG.3

FIG.4

FIG.5

FIG.6

FIG. 7

FIG. 8

FIG. 1 is an exploded perspective view of a combined brush and sponge, showing my new design;

FIG. 2 is a view similar to FIG. 1, but showing the parts in combined form;

FIG. 3 is a side elevational view thereof;

FIG. 4 is a bottom plan view thereof;

FIG. 5 is an end elevational view thereof;

FIG. 6 is a sectional view along the line 6—6 of FIG. 5;

FIG. 7 is a side elevational view of the modified design; and

FIG. 8 is an end elevational view of the modified design of FIG. 7.

The broken lines shown in FIGS. 3 and 7 represent bristles omitted for convenience of illustration.

It is to be understood that the broken lines shown in

FIG. 4 represent bristles omitted for convenience of illustration, and that the pattern of ornamentation partially shown is intended to encompass the entire area contemplated thereby.

I claim:

The ornamental design for a combined brush and sponge, as substantially shown and described.
